UNITED STATES PATENT OFFICE.

HARRY J. HICK, OF ALLIANCE, OHIO, ASSIGNOR TO THE McCASKEY REGISTER COMPANY, (INCORPORATED IN 1914,) OF ALLIANCE, OHIO, A CORPORATION OF OHIO.

FILING-APPLIANCE CASE.

1,242,440.

Specification of Letters Patent.

Patented Oct. 9, 1917.

Application filed July 27, 1914. Serial No. 853,254.

To all whom it may concern:

Be it known that I, HARRY J. HICK, a citizen of the United States, residing at Alliance, in the county of Stark and State of Ohio, have invented certain new and useful Improvements in Filing-Appliance Cases, of which the following is a specification.

The invention relates to a case for a filing appliance, which may include a series of 10 hinged holders operatively mounted therein and adapted to be completely inclosed by the case for protection against fire and like damage.

The invention contemplates the use of a 15 rectangular case composed of a lower or base section and an upper or cover section, with guiding hinge connections between the sections, so that the upper section can be closed downward upon the base section to 20 completely incase the bill holders mounted therein, or can be swung upward with its rear end resting upon the rear portion of the base section to form a back or support for the bill holders in operative position.

25 In a former application, filed June 1, 1914, Serial No. 841,976, a filing appliance of this type or character has been illustrated, described and claimed, in which similar base and cover sections are provided with intermeshing tongues and grooves upon the side and forward rims and rabbets upon the rear rims, and with guiding hinge connections 30 between their rear ends for swinging and shifting the cover sections upon the base sections, so that when closed the rear ends will 35 be in alinement, and when open, the top of the cover section will be alined with the rear end of the base section.

The object of the present invention is to 40 provide intermeshing tongues and grooves upon the rear rims of the case sections, as well as upon the side and forward rims thereof; and to construct and arrange the guiding hinge connections so as to disengage 45 and reengage the intermeshing tongue and groove upon the rear rims before and after the shifting of the cover section upon the base section caused by its opening and closing movements.

50 The object of the invention, thus briefly set forth, is attained by the preferred embodiment thereof illustrated in the accompanying drawings, forming part hereof, in which—

55 Figure 1 is a side elevation of the case

with the cover section closed upon the base section;

Fig. 2, a similar view showing the cover section rotated part way into upright position upon the rear end of the base section, 60 and showing one guiding hinge connection, partly in section thereon;

Fig. 3, a similar view partly in section showing the cover section rotated into upright position upon the rear end of the base 65 section; and

Fig. 4, a fragmentary rear end view of one side of the case with the cover section rotated part way upward as in Fig. 2.

Similar numerals refer to similar parts 70 throughout the drawings.

The case is composed of the substantially similar rectangular bottom or base section 1 and the top or cover section 2, which are operatively connected together by means of 75 the guiding hinge brackets 3, one being located on each side of the rear end portion of the case. A series of bill holders 4 may be hinged together at their rear ends, and the lower holder may have its hinged end 80 pivoted to the rear end rim of the cover section; and all the holders may be superposed upon an index frame 5, also pivoted at its rear end to the rear rim of the cover section and having its forward end supported 85 by guiding means 6 for operating forward and rearward out of and into the case.

Each wall of the case sections is preferably made of two metal sheets or plates 7, spaced apart, between which is provided the 90 filling 8 of heat resisting material to form a fire-proof structure; and the rims of the case sections are preferably formed by welding or otherwise securing bars of substantially rectangular cross section, between 95 the edges of the spaced metal plates. The rim bars 9 of one section, preferably the base section, are provided with the tongues 10, and the rim bars 11 of the other section, preferably the cover section, are provided 100 with the corresponding grooves 12; which tongues and grooves are arranged to intermesh with each other to form a sealed joint between the rims, when the cover section is seated upon the base section, as shown in 105 Fig. 1.

Each guiding hinge bracket 3 is secured by the depending flange 13 thereon to the side of the base section at the rear end thereof, as by means of the bolts 14; and in each 110

bracket is formed the horizontal way 15, above and adjacent to the rim of the base section, and the upright way 16 above the horizontal way and intermediate the ends thereof.

5 The horizontal way 15 may be formed by flanges deflected outward from the body of the bracket forming the horizontal track 17 below and the horizontal guide 18 above the way; and the horizontal track is preferably located slightly above the top of the rim tongue 10 on the base section, and for the purpose of the present invention, the rear end of the track is depressed to form the 10 circular segment socket 19, the bottom of which extends to or below the base of the rim tongues 10.

15 And the upright way 16 may likewise be formed by flanges deflected outward from the body of the bracket to form the guides 20 and 21 on the forward and rear sides of the way; which guides are preferably parallel to each other, and have their upper portions substantially vertical and the 20 lower portions inclined downward and forward from the upper portions, the inclined lower portions of the guides being curved concentric with the rear edge of the rear rim of the base section.

25 30 Rollers 22 are pivoted on each side of the lower rear corner of the cover section, which rollers are arranged to travel in the horizontal ways 15 and to rest in the circular-segment sockets 19 at the rear end of the ways 35 when the cover section is closed downward upon the base section; and rollers 23 are journaled on each side near the rear end of the cover section intermediate its top and rim, which rollers are arranged to travel 40 in the upright ways 16.

45 Lock plates 24 are secured to each inner side of the cover section at the rear end thereof, and are provided with the inclined hooks 25 protruding from the rear rim of the cover section, so as to engage with the lock posts, which may be the pivoted rollers 26, mounted on each inner side of the base section adjacent to the rear rim thereof, for drawing the pivot rollers 22 directly downward into the sockets 19 and clamping the 50 rear ends of the case sections together when the cover section is rotated downward, to seat its rim grooves upon the rim tongues of the base section.

55 60 Counterbalance means are provided for sustaining the cover section when swung upward from the base section, which means may include bearing heads 27 pivoted to the forward part of the base section, slide brackets 28 pivoted to the sides of the cover section, slide rods 29 secured to the bearing bracket and operating in and through the slide brackets, and compression springs on the slide rods between the brackets. For the 65 purpose of the present invention, the springs

in the counterbalance means may be made strong enough so that when the cover section is closed downward upon the base section, the action of the springs will tend to raise the cover section bodily upward from the base section.

70 The parts are so proportioned and arranged that when the cover section is swung downward upon the base section, the rollers 22 will ride rearward upon the tracks 17 75 into the sockets 19 at the rear end of the ways 15, and the rollers 23 will be guided downward in the ways 16, until they reach the curved lower portion thereof, when the forward guide 20 and the clamping hook 25 80 will force the rear rim of the cover section directly downward upon the rear rim of the base section after which the roller 23 will travel downward and forward in a circle concentric with the rear edge of the rear 85 rim of the base section, the forward guide 20, supplemented by the clamping hook and post 25 and 26, serving to force and clamp the cover rim downward upon the base rim of the case.

90 Suitable locking and clamping means including the hook latch 30 in the forward end of the cover section and the post 31 in the forward end of the base section may be provided for locking and clamping the forward 95 ends of the case sections together. In this relation of the parts, it is evident that a sealed air-tight joint will be maintained between the rims, which will prevent the entrance of fire flames or heat therethrough 100 into the case. And furthermore, the entrance of the tongues between the grooves in all the rims will hold the adjoining rim in true alinement and prevent a lateral warping of one with reference to the other, and 105 a consequent gapping of the joint.

110 For opening the case, after unlocking the latch 30, the cover section may be swung upward by grasping the handle 32 on the forward end thereof; in which movement the cover section will first rotate upward upon rear edge of the rear rim of the base section, until the rollers 23 reach the vertical portion of the upright ways; whereupon the counterbalance springs, supplementing the 115 lifting action of the operator, will raise the cover sections directly upward so that the rear rim thereof will clear the tongues on the rear rim of the base section, thereby permitting the rear rim of the cover section to move freely forward, with the rollers 22 thereon riding upon the tracks 17; the rollers 23 between the guides forming the upright way 16, now serving as a fulcrum, as shown in Fig. 2, until the cover section of 120 the case has been shifted into upright position upon the base section, as shown in Fig. 3.

125 For closing the cover section upon the base section, the operation thus described 130

is just reversed; and it is evident that after the rear rim of the cover section has been swung backward freely over the tongue on the rear rim of the base section, by a movement reverse to that described above, the rollers 23 will be forced downward by the guides 20, which action will finally be supplemented by the locking hook 26 and latch 30, to draw the cover section downward 10 against the sustaining action of the counter-balance springs, thereby seating and clamping the case rims securely together.

In order to prevent any binding action of the rollers in the guide-ways during the 15 initial opening and final closing movements of the cover section upon the base section, the segment sockets 19 are preferably formed slightly larger than the rollers 22 so as to operate freely therein; and to further facilitate the swinging of the cover section, the intermeshing tongues and grooves on the rims of the cover and base sections are tapered so as to permit a free and easy disengagement thereof.

25 I claim:

1. A filing case including a stationary member and a movable member, connections between said members permitting the movable member to swing relative to said stationary member, and operating to move it longitudinally of said stationary member, and to move it directly upward or downward during an intermediate portion of said swinging movement.

35 2. A filing case including a stationary member and a movable member, cam connections between said members permitting the movable member to swing relative to said stationary member and operating during the 40 swinging movement of the movable member to move said movable member longitudinally of said stationary member, with a directly upward or downward movement during an intermediate portion of said swinging movement.

45 3. A filing case including a bottom member, an upper member mounted on and movable relative to said bottom member, and cooperating cammed connections between said 50 members permitting the upper section to swing relative to said bottom section and operating to move said upper section longitudinally of said bottom section as it swings from one position to another, with a directly upward or downward movement during an intermediate portion of said swinging movement.

55 4. A filing case including two sections, and connections between said sections permitting 60 one of them to be swung relative to the other and operating to cause longitudinal movement between the sections during the swinging movement of the movable section, with

a directly upward or downward movement during an intermediate portion of said 65 swinging movement.

5. A filing case including two sections, one of which is movable relative to the other from an upright to a horizontal position and vice versa, and means joining said sections together, whereby movement of the movable section from one position to the other actuates said movable section in a longitudinal direction, and also directly upward or downward during an intermediate 75 portion of said swinging movement.

6. A filing case including a base section and a cover section thereon, and guiding hinge connections between the rear ends of the sections comprising brackets on the base 80 section having horizontal tracks with circular segment sockets in their rear ends adjacent to the rims thereof, upright guide-ways having their lower ends curved concentric with the rear edge of the rear rim 85 of the base section, and pivots on the cover section operating upon the tracks and in the guideways.

7. A filing case including similar base and cover sections with guiding hinge connections between their rear ends for swinging and shifting the cover section upon the base section, there being intermeshing tongues and grooves upon all the rims of the section, and means for moving the cover section directly upward and downward before and after the shifting movement thereof.

8. A filing case including similar base and cover sections with guiding hinge connections between their rear ends for swinging 100 and shifting the cover section upon the base section, there being intermeshing tongues and grooves upon all the rims of the sections, and means for moving the cover section directly downward and then clamping and 105 locking the rims together when the case sections are closed, and vice versa.

9. A filing case including similar base and cover sections with guiding hinge connections between their rear ends for swinging 110 and shifting the cover section upon the base section, there being intermeshing tongues and grooves upon all the rims of the sections, the hinge connections permitting a vertical movement of the cover section at 115 a predetermined place intermediate the ends of the swinging movement, and correlated means for raising and lowering the cover directly upward or downward at said predetermined place to clear the tongue upon 120 the rear rim of the base section.
